UNITED STATES PATENT OFFICE.

ROBERT P. CREED, OF CLEVELAND, OHIO.

DESIGN FOR A MANTEL ORNAMENT.

SPECIFICATION forming part of Design No. 25,571, dated June 2, 1896.

Application filed March 23, 1896. Serial No. 582,485. Term of patent 3½ years.

To all whom it may concern:

Be it known that I, ROBERT P. CREED, a citizen of the United States, and a resident of Cleveland, in the county of Cuyahoga, State of Ohio, have invented and produced a new and original Design for Mantel Ornaments, of which the following is a specification, reference being had to the accompanying drawings, showing a part thereof.

10 Figure 1 is a perspective view showing front and side elevation. Fig. 2 is a similar view showing rear elevation and the side not shown in Fig. 1.

15 In the views, 1 is a flat-topped round tower forming the prominent feature of the design. In front of this tower is the rectangular shallow porch 2, of the full width of the tower, and 3 3 are smaller octagonal towers placed at the angle of jointure of the porch and main tower.

20 These towers are also flat-topped.

4 is a base slightly larger than the towers and porch and conforming in a general way in outline with them. The outer and upper edge of this base is beveled at 5.

25 The detail designs upon the towers and porch are as follows: A heavy coping 6 surrounds the large tower, and a row of columns 7 and Gothic arches 8 separates the upper and lower portions. A broad band 9 encircles the tower below the columns. In the

30 rear is placed a single Gothic window 10, and in front are two similar windows 11, sepa-

rated by a column 12. The rear lower portion of the large tower is pierced with Gothic windows 13, separated by smooth vertical bands 14, and an inclined band 15 separates the upper portion of the tower from the lower immediately above the windows. The lower windows 13 of the tower are peculiar in having a large upper arch and smaller arches 16 filling the lower portion of the windows. The porch is provided with a large equilateral main arch 1, extending to the base, and smaller side arches 18. Similar small arches 19 are pierced in the side of the porch. A 45 railing 20, pierced with trefoils 21, surmounts the porch, and similar railings 22 surmount the small towers, which are a little higher than the porch. A projecting molding 23 is placed under the railing on the porch, and 50 underneath this molding is placed the ornamental bond 24, paneled with designs representing tobacco and tobacco implements—viz., the center panel shows crossed pipes, one end cigars, and the other a tobacco-plant. 55 Underneath the main arch in the porch are placed columns with ornamental capitals.

What I claim is—

The design for a mantel ornament, substantially as set forth.

ROBERT P. CREED.
